REFRIGERATED DISPLAY CASE

George K. Bently and Walter D. Crowl, Kendallville, Ind., assignors to McCray Refrigerator Company, Inc., Kendallville, Ind., a corporation of Indiana

Filed Nov. 7, 1960, Ser. No. 62,750

Term of patent 14 years

(Cl. D80—11)

FIG. 1 is a perspective view of a refrigerated display case embodying our new design;

FIG. 2 is an elevational view of the end opposite that shown in FIG. 1; and

FIG. 3 is a vertical section taken on line 3—3 of FIG. 1.

The side not shown in a mirror image of the side shown. The internal walls and bottom portions not shown are substantially plain.

The design for the refrigerated display case disclosed is characterized by the upper fluted panel and the corner members thereon as shown.

We claim:

The ornamental design for a refrigerated display case, as shown and described.
